UNITED STATES PATENT OFFICE.

WILLIAM E. DE LHORBE, OF CHICAGO, ILLINOIS.

COLLAPSIBLE CORE FOR PLASTIC BUILDING-WALLS.

No. 839,818.

Specification of Letters Patent.

Patented Jan. 1, 1907.

Application filed May 17, 1906. Serial No. 317,334.

To all whom it may concern:

Be it known that I, WILLIAM E. DE LHORBE, a citizen of the United States, residing at Chicago, in the county of Cook and State of Illinois, have invented a certain new and useful Improvement in Collapsible Cores for Plastic Building-Walls, of which the following is a specification.

My invention relates to collapsible cores for producing air-spaces in building-walls formed of cement or other plastic material.

The object of the invention is to provide means whereby an air space or duct may be formed within the wall without lateral apertures running to the surface of the wall, and also to produce such ducts or spaces continuously as the wall rises in process of construction. Briefly speaking, this object is obtained by means of a collapsible tube provided with means whereby it may be collapsed after the wall has more or less completely set or hardened around it.

I attain my object by the apparatus shown in the accompanying drawings, in which—

Figure 1 is a horizontal section of a building-wall, showing air-spaces. In two of these spaces my collapsible core is shown in position. Fig. 2 is a side elevation of the core. Fig. 3 is a sectional elevation taken longitudinally through the greatest dimension thereof and showing the collapsing and expanding mechanism. The view shows the core in expanded position. Fig. 4 is similar to Fig. 3, but shows the tube in collapsed or contracted position. Fig. 5 is a horizontal sectional view taken on line 5 of Fig. 3, drawn to an increased scale and showing a section of building-wall with the core in place therein and in collapsed condition.

Similar letters refer to similar parts throughout the several views.

The shell *a* or core proper consists, preferably, of sheet metal of such stiffness as to withstand the lateral pressure of the plastic material of which the wall *b* is to be composed, said core being sufficiently flexible to be collapsible under the action of proper mechanism when the core is to be withdrawn. The precise cross-sectional configuration of the core is not essential, but in the preferred form the sides are approximately parallel and the ends round, it being obvious, however, to those skilled in the art that in cross-section the core might be circular or elliptical or modified from either of these forms. The core is not a complete tube, however—

that is, is not continuous in its periphery, but is split along the side, and the edges *a'* and *a²* of the core lap a slight distance. The height of the core is not essential, and this dimension may be altered to suit the convenience of different users.

The preferred mechanism for holding the core in collapsed or expanded position is best illustrated in Figs. 3 and 4, in which *c* represents a controlling-rod, which is connected to one overlapping edge *a'* by means of links *d*, which links are pivoted at *d'* to said rod and at *d²* to the core-lap *a²*. Said rod is vertically slideable in the guide-straps *e*, rigidly secured to the inside of the core at the remaining overlapping edge *a²* thereof. Said guide-straps *e* prevent lateral movement of said rod with reference to the core, and in order to stiffen said guide-straps the free extremities thereof are passed beneath keepers *f*, rigidly secured on the opposite lap *a²*. The parts are so arranged that the rod *c* is vertically movable within the guide-straps *e*, and said guide-straps at their free extremities are horizontally slideable within the keepers *f*. It is desirable to provide an eye *c'* at the upper extremity of rod *c* for manipulating it by hand or tackle.

In the operation of the apparatus the core is first set in upright position with the controlling parts in the condition shown in Fig. 3, in which the links *d* are approximately at right angles to the overlapping edges *a'* *a²*. Under these conditions the core is expanded to its greatest size. The cement or other plastic material on which the wall is to be built is then built up around the core in the usual manner, the area occupied by the core forming a dead-air space in the wall, as indicated in Figs. 1 and 5. The core tends to maintain itself in expanded position notwithstanding the lateral pressure of the building material, for the reason that the links *d* occupy a position which might be referred to as "dead-center"—that is to say, they lie in a direction coincident with the lines of pressure of the building material upon the core. After the wall has risen to a height more or less closely approaching the upper end of the core, allowing sufficient time to elapse for the material to more or less completely set or harden, a block and tackle, derrick, or other suitable elevating mechanism, or in the case of small cores the hand of the operator, is applied to the rod *c*—for example, at the eye *c'* therein—and caused to raise said rod. The

raising of the rod while the core still remains in place causes the links d to rotate about their pivots d^2 on the edge a^2 , thus drawing said edges a' and a^2 together to increase the overlap thereof. This contracts the core, and consequently loosens it not only from the ends, but draws the exterior surface thereof away from the interior surface of the space within the wall. Thus the core be-
10 comes loosened, and by the continuously-up-
ward pulling movement on the rod c the core may be lifted out. Inasmuch as the operating parts are all inside of the tube, there is nothing to become embedded in the cement
15 of the wall and nothing to interfere with the free withdrawal of the core from the wall. Although the outer overlapping edge a^2 may engage a slight ridge or shoulder formed by its presence within the wall, the inner edge a^2
20 is free to telescope within said outer edge, and it is therefore unnecessary for both edges to be movable within the wall.

As a result of the above construction it is clear that under ordinary conditions no matter how hard the wall becomes it is merely necessary to pull upward upon the controlling-rod c , when the core will be loosened from the wall and pulled up out of the same with practically a single continuous movement of said controlling-rod.

It is obvious, of course, that in constructing the wall it is not necessary to completely withdraw the core, for its lower extremity may be left within the wall and the wall continued up around it, thus rendering it possible with a short core to form a continuous air-space of greater length than the length of the core.

I desire to call especial attention to the fact
40 that the core is self-clamping or self-locking in expanded position. No matter how great is the pressure of the surrounding material

upon the sides of the core all that is necessary is to force the controlling-rod c down until the links d are horizontal—that is, in line 45 with the direction of each lateral pressure. No locks or clips or removable pieces are necessary, and the whole apparatus constitutes a single coöperative mechanism.

What I claim as new, and desire to secure 50 by Letters Patent, is—

1. A sheet-metal core for building-walls having its longitudinal edges overlapping; links pivoted to the inside of said core near one edge, and a member longitudinally slid- 55 able but laterally fixed with reference to the opposite edge of said core and pivoted to the remaining ends of said links substantially as described.

2. A sheet-metal core for building-walls 60 having its longitudinal edges overlapping; links pivoted to said core on one side of the overlap; a controlling-rod also pivoted to said links; and guides for said controlling-rod mounted on said core on the other side of said 65 overlap.

3. A sheet-metal core for building-walls having its longitudinal edges overlapping; links pivoted to said core on one side of the overlap; a controlling-rod also pivoted to 70 said links; guides for said controlling-rod mounted on said core on the other side of said overlap, said guides being extended across said overlap; and keepers for said guide extensions which keepers are fastened 75 to the core on the same side of the overlap with the link-pivots.

In witness whereof I have hereunto subscribed my name in the presence of two witnesses.

WILLIAM E. DE LHORBE.
